ADJUSTABLE GUIDE ARM

Ross P. Baldwin, Drexel Hill, Pa.

Application January 17, 1934, Serial No. 306,947

5 Claims. (Cl. 4—57)

My invention relates to new and useful improvements in an adjustable guide arm for use in connection with toilet flush tanks and has for one of its objects to provide a device of this character wherein the guide arm may be securely attached to any one of a number of different sized overflow pipes and the guide for the stem of the float valve then positioned so as to be in endwise alignment with the center of the valve seat.

Another object of the invention is to provide, as an article of manufacture, an adjustable guide arm capable of adjustment for the purpose of clamping it on an overflow pipe as well as properly centering the guide for the float valve stem.

A further object of the invention is to construct an adjustable guide arm as a unitary assembled structure which may be readily clamped on an overflow pipe and the guide means for the float valve stem quickly adjusted for positioning the same in the proper location relative to the center of the valve seat.

Generally, at the present time, flush tank fixtures are constructed with a number of different sized overflow pipes and the distances between the centers of the overflow pipe and its associated valve seat vary considerably. Where a guide arm is manufactured for use with the largest size overflow pipe, it is very difficult to properly attach it to one of the smaller sizes and where the guide means is fixed relative to the collar which is attached to the overflow pipe the float valve will not properly seat unless the distances happen to be correct for the fixture on which the arm is used. These disadvantages are entirely overcome by my device because when clamped on the overflow pipe there are at least five bearing points which give a good grip on the pipe and prevent any possibility of tilting from one side to the other and after being mounted in place the guide can be accurately adjusted relative to the center of the valve seat so that the valve will always properly close the outlet.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to

the accompanying drawing forming a part of this application, in which:—

Fig. 1 is a view illustrating the manner of using my invention.

Fig. 2 is an enlarged perspective view of the adjustable guide arm embodying my invention.

Fig. 3 is a plan view thereof with the clamping nut in a slightly different position.

Fig. 4 is a section on the line 4—4 of Fig. 3 and showing the use of the lock nut.

In carrying out my invention as herein embodied, 5 represents a conventional illustration of the flushing fixture of a toilet flush tank including an outlet 6 surrounded by a valve seat 7 and carrying an overflow pipe 8. The outlet is normally closed by a float valve 9 provided with a stem 10 which is connected with a valve lever mechanism, a portion of which is shown at 11, for unseating the valve.

The adjustable guide arm 12 includes a solid 20 ring 13 carrying an externally threaded spindle 14 which has a slot 15 formed therethrough longitudinally thereof and projecting vertically or parallel with the bore through the ring.

On the spindle is slidably mounted a clamping jaw 16 including a pair of lips 17 spaced a distance approximately equal to the width of the ring so as to embrace the latter for adjustment relative thereto. Each lip has a V-shaped notch 18 formed therein which provides bearing surfaces for contact with the overflow pipe on which the device is mounted. Said clamping jaw is moved forwardly for adjustment purpose and held in any adjusted position by a nut 19 or equivalent means screwed on to the externally threaded spindle 14.

On the threaded spindle 14 is also mounted a guide element 20 which also has threaded connection with the spindle and said bearing member has a hole 21 extending completely through the same in a straight line so that when said bearing member is properly positioned the hole therethrough will align with the slot 15 and permit passage of the stem 10 of the float valve. It will be obvious that the nut 19 and the bearing member 20 may be duplicates of each other or they may be similar except as to size so that in production it will be unnecessary to make tools for two dissimilar parts. It will also be understood that if more accurate adjustments for the bearing member are desired, additional holes may be formed in said bearing member.

In practice, the ring 13 has an inside diameter at least equal to the outside diameter of the largest overflow pipe used in toilet flush

tanks and then by slipping the ring over any overflow pipe the adjustable guide arm may be securely clamped thereon by screwing the nut 19 forward or toward the ring. This will force 5 the lips of the clamping jaw 16 against parts of the overflow pipe and draw the side of the ring 13 opposite the clamping jaw against another part of the overflow pipe until the adjustable guide arm is securely fastened. When the 10 device is properly mounted on the overflow pipe there will be at least five points of contact on the overflow pipe thereby overcoming any chance of oscillatory movements which not only tend to loosen the arm from the pipe but also throw 15 the bearing out of proper alignment.

Next the bearing member is screwed in or out as the case may be to adjust it relative to the valve seat 7, which adjusting movements are continued until the hole 21 in said bearing member 20 is above the center of the valve seat. After 25 the adjustment is obtained, the valve stem 10 is projected through the hole 21 and the slot 15 and then permanently connected to the float valve 9. The assembling of the valve stem in the bearing member prevents rotation of the latter on the spindle 14 thus securing said bearing member in its adjusted position.

In order to temporarily hold the bearing member 20 in a fixed or adjusted position a lock or 30 jamb nut 22 may be screwed onto the spindle 14 and caused to engage said bearing member.

Of course I do not wish to be limited to the exact details of construction herein shown and described as these may be varied within the 35 limits of the appended claims without departing from the spirit of my invention.

Having thus fully described my invention, what I claim as new and useful is:—

1. An adjustable guide arm comprising a ring, 40 an externally threaded longitudinally slotted spindle supported by said ring, means adjustably mounted on said spindle and coacting with the ring to clamp the arm on an overflow pipe, and an apertured bearing member adjustably 45 mounted on the spindle and adapted to guide a valve stem passing through the aperture and the slot in the spindle.

2. An adjustable guide arm comprising a ring adapted to encircle an overflow pipe, an externally threaded and longitudinally slotted spindle carried by said ring, a clamping jaw slidably mounted on the spindle and embracing the ring for clamping the overflow pipe between a portion of said jaw and the ring, means having threaded connection with the spindle and coacting with the clamping jaw to force the same forward relative to the ring, and an apertured guide having threaded connection with the spindle for adjustment lengthwise thereof to vary the distance between the center of the overflow pipe on which the device is clamped and the center of the aperture through the guide, said aperture 10 adapted to align with the slot in the spindle to permit the projection of a valve stem there-through.

3. The structure set forth in claim 2, wherein the clamping jaw includes a pair of lips having 20 V-shaped notches therein.

4. An adjustable guide arm consisting of a solid ring adapted to encircle an overflow pipe, an externally threaded spindle projecting from said ring and having a longitudinal slot formed 25 therein parallel with the opening through the ring, a clamping jaw slidably mounted on said spindle and including a pair of lips adapted to project over the ends of said ring, said lips having V-shaped notches therein to provide a plurality of contact surfaces which engage the overflow pipe at separated locations to hold the guide arm in a steady condition, means having threaded connection with the spindle to move the clamping jaw forward relative to the ring, and 30 other means also having threaded connection with the spindle whereby said means may be adjusted longitudinally of the spindle and said means having an aperture therethrough adapted to be moved into alignment with the slot to 35 permit passage of a valve stem whereby the latter will be guided.

5. The structure in claim 1, in combination with a jamb nut screwed onto the spindle and engaging the bearing member.

ROSS P. BALDWIN.
